DESIGN FOR A CHILD'S STOCKING

Harold Mange, St. Louis, Mo.

Application January 13, 1936, Serial No. 60,560

Term of patent 7 years

To all whom it may concern:

Be it known that I, Harold Mange, a citizen of the United States, residing at the city of St. Louis, State of Missouri, have invented a new, original, and ornamental Design for a Child's Stocking, of which the following is a specification, reference being made to the accompanying drawing, forming a part thereof, in which Figure 1 is a side elevational view and Figure 2 is a front elevational view of a child's stocking embodying my design.

I claim—

The ornamental design for a child's stocking substantially as shown.

HAROLD MANGE.
